UNITED STATES PATENT OFFICE.

LUTHER ASHLEY FAUGHT, OF PHILADELPHIA, PENNSYLVANIA, ASSIGNOR
TO THE WILMINGTON DENTAL MANUFACTURING COMPANY, OF SAME
PLACE.

ELECTRO-DENTAL HEATER.

SPECIFICATION forming part of Letters Patent No. 439,238, dated October 28, 1890.

Application filed July 23, 1890. Serial No. 359,631. (No model.)

To all whom it may concern:

Be it known that I, LUTHER ASHLEY FAUGHT, a citizen of the United States, residing at the city of Philadelphia, in the county 5 of Philadelphia and State of Pennsylvania, have invented certain new and useful Improvements in Electro-Dental Heaters, of which the following is a specification.

My invention relates to a portable electrical 10 heating appliance or instrument for use in dental surgery.

Heretofore it has been customary in order 15 to fill the cavity of a tooth with gutta-percha or with similar material, or to otherwise manipulate such materials in the mouth in relation with tooth substances, to first apply such material or materials thereto, and then by means of a simple dental tool exposed at intervals to a flame or otherwise warmed to 20 press the material firmly therein, so that it might to a greater or less degree become set in the cavity.

The principal object of my invention is to provide, first, a simple, durable, and effective 25 heating appliance for the working of gutta-percha or somewhat similar material or substances into indentures or cavities formed in the teeth of the mouth; second, to provide an effective appliance for readily transmitting the requisite amount of heat to artificial 30 crowns, veneers, or parts of crowns provided with pins or pieces of porcelain without pins for permitting of their insertion into apertures or cavities prepared to receive them in natural teeth or roots in the mouth, and, third, to provide an effective device for transmitting heat by means of an instrument or probe for the purpose of warming or drying the canals in the roots of teeth.

40 My invention consists of a portable electro-dental heating device constructed, arranged, and operating substantially in the manner hereinafter described, and pointed out in the claims.

45 Referring now to the accompanying drawings, Figure 1 is an elevational view of an electro-dental instrument containing or embodying the particular characteristic features of my invention. Fig. 2 is a vertical central 50 section of the heater, having an incandescent

electric lamp mounted therein or other resistance or heat-generating device placed in the path of an electric current and with two conductors leading therefrom to a source of electric energy, and with a suitable tool applied 55 to the upper end thereof for working the filling; and Fig. 3 is a similar view of a portion of an instrument embodying the features of my invention and adapted to permit of the heating of artificial crowns, veneers, or parts 60 of crowns for securing the same in cavities prepared to receive them in the mouth.

Referring to the drawings, *a* is the holder or housing, made of wood or other suitable insulating material, provided at the lower extremity with a removable button *b* and at the opposite extremity with a tapering or other suitable form of cap *c*, having a recess *c'* adapted to receive a point or other suitable dental tool; or the recess or cavity *c'* may be 70 made in such form as to permit of an artificial crown *d*, being mounted therein, as shown, for instance, in Fig. 3, for securing the same into a natural tooth or root in the mouth.

e is an incandescent lamp or other heat-generating appliance mounted in one end of the holder *a* and provided with conductors or wires 1 and 2, having terminals 3 and 4 for connection with a suitable type of battery or other source of electric energy 5. The cap *c*, 80 made of aluminum or other good conducting material suitably secured to the holder *a*, is provided with one or more apertures *f*, in order that the operator may readily ascertain from time to time whether the lamp is being 85 maintained in the proper state of incandescence during application or use of the instrument. The cap *c*, applied to the instrument, whether of tapering form, as shown in Figs. 1 and 2, or of a form adapted to receive an artificial crown, as shown in Fig. 3, is made of a metal or material that will readily conduct heat from the lamp *e* or other resistant material or heat-generating device so long as a current is permitted to pass from a source of energy 5 95 thereto, and while the filling of the cavity is being carried on by the operator. It will be observed that as the instrument is arranged, in case of breakage of the lamp the cap *c* may be readily removed, and as well the but- 100

ton *b* at the opposite end of the holder *a*, for permitting of the withdrawal of the lamp with its two wires or conductors from the battery for the supplying of another thereto.

- 5 The particular feature or advantage of my invention is that an efficient heater for dental operations is always had, and such as can be maintained at the required temperature *ad libitum* for the working of gutta-percha or 10 other similar material or fillings into cavities in the teeth, or otherwise, in contradistinction to the methods heretofore employed for the working of such fillings by using a simple hand-tool heated first in a flame or over a 15 heater and then brought into contact with the filling. Such a method consumed time, and the operation of filling a tooth in such manner was not at all satisfactory, owing to the fact that the operator had to continually 20 expose the tool to the heat of a spirit-lamp flame or heater and then the tool became cool almost before it could be applied to the filling. This serious disadvantage is entirely obviated by the use of a heater of the type 25 hereinbefore described. In practice it has been found that the points or other tools adapted for use in connection with said heater give most satisfactory results when made of aluminum or other good heat-conducting material. Furthermore, it has been found that 30 a lamp of from two to five candle power is sufficient, ordinarily, for the working of a filling of the character described; but, however, I do not wish to be understood as limiting 35 myself to the use of a lamp of such candle-power, exclusively, in such a heater.
- The construction of heater illustrated in Fig. 3 is the same as that illustrated in Figs. 1 and 2, with this exception, that the upper 40 removable cap *c* is provided with a sunken head instead of being made tapering for the reception of a point or other tool for working the filling in the cavity or causing the same to become firmly set therein. The sunken 45 head of the cap *c* is adapted to receive an artificial crown provided with a pin or dowel, or veneer, or parts of crowns with or without pins, so that when the cap has been heated up by the lamp *e* it will transmit its heat there- 50 from to and maintain it in the artificial tooth, and its pin of platinum or other material soft- 55 ening the material applied thereto and also that embedded in the cavity prepared to receive the same, in order that when the heater is removed the artificial crown may become

firmly fixed in the required position in the mouth.

Having thus described the nature and objects of my invention, what I claim as new, and desire to secure by Letters Patent, is— 60

1. An electro-dental heating device provided with a lamp connected with a source of electric energy and having a cap of conducting material provided with a recess or cavity, substantially as and for the purposes set forth. 65

2. A dental heating appliance having a holder within which is concealed an electric heat-generating device connected with a source of energy, and the holder provided with a cap of conducting material having a 70 recess for supporting a tool, substantially as and for the purposes set forth.

3. An electro-dental heating device provided with an insulating-holder within which is mounted an electric lamp connected with 75 a source of energy, and the holder provided with a removable cap of conducting material, having a tapering recess therein for receiving a point or other tool of similar material, substantially as and for the purposes set forth. 80

4. An electro-dental heating device having a lamp mounted therein and connected with a source of electric energy, and a cap provided with a recess for receiving a point or artificial crown, substantially as and for the 85 purposes set forth.

5. A dental heating instrument having therein a lamp provided with conductors adapted to be connected with a source of electric energy, a conical-shaped cap of conducting material, having an aperture or apertures formed therein, and the cap provided with a recess for receiving and holding a point or other suitable device, substantially as and for the purposes set forth. 95

6. A dental-heating instrument having a holder provided with an electric lamp or other heat-generating appliance, a button applied to one end of the holder, and a removable recessed cap connected with the opposite end 100 and adapted to permit of the insertion of a tool or other article into or onto said cap, substantially as and for the purposes set forth.

In witness whereof I have hereunto set my signature in the presence of two subscribing 105 witnesses.

LUTHER ASHLEY FAUGHT.
